UNITED STATES PATENT OFFICE.

SAMUEL M. FULTON, OF POMONA, CALIFORNIA.

PUMP-HEAD.

1,382,281.

Specification of Letters Patent. Patented June 21, 1921.

Original application filed January 14, 1920, Serial No. 351,480. Divided and this application filed August 7, 1920. Serial No. 401,838.

To all whom it may concern:

Be it known that I, SAMUEL M. FULTON, a citizen of the United States, residing at Pomona, in the county of Los Angeles, State 5 of California, have invented a new and useful Pump-Head, of which the following is a specification.

This invention relates to pump heads, and particularly to a mechanism for imparting 10 a variable driving motion to a plurality of plungers to secure a continuous flow, such mechanism being of the type shown and described in my application, Serial No. 351,480, filed January 14, 1920, of which this

15 application is a division.

The invention has for an object to improve the construction of driving mechanism for a plurality of plungers whereby a slow upward stroke is imparted to one plunger 20 while the other is effecting a quick downward stroke.

A further object of the invention is to so construct and arrange the driving means that a lap of the plungers at the end of 25 each stroke is secured—that is, one plunger will start upward and take the load prior to the completion of the downward stroke of the other plunger, whereby the column of water is kept in motion and the hammer or 30 jar due to stopping and starting of the column of water entirely obviated.

A further object of the invention is to improve the details of construction of the driving mechanism and the connection 35 therefrom to the plunger rods.

Figure 1 is a front elevation of the pump head, some of the parts being in section, and the well pit, well casing and discharge pipe being shown in section.

40 Fig. 2 is a top plan view.

Fig. 3 is a side elevation.

Fig. 4 is a detailed side elevation of one of the walking beams.

Fig. 5 is a detailed vertical section 45 through the cross head and pump rods.

Fig. 6 is a detail elevation of the crank shaft.

In the drawings 1 designates a foundation 50 preferably formed of concrete and provided with a rectangular well pit 2. Embedded in the concrete foundation with the upper surfaces lying flush with the upper surface of said foundation I provide opposed horizontal tracks, each formed of parallel I beams 55 3, 4 separated to form longitudinal inter-

mediate slots 5. (See Figs. 1, 2.) The beams 3, 4 are held in spaced relation by spacing blocks 6 which are maintained in position by transverse bolts 7, 8 extending through alined orifices in the beams and in 60 the blocks. The frame which supports the operating mechanism comprises two opposed side frames 9, 10 longitudinally slidable upon the I beam tracks or sills and maintained in spaced relation by a tie bar or 65 yoke 11 secured to the upper forward ends of the side frames. The frame is secured in adjusted position upon the tracks by bolts 12 and nuts 13.

The main drive shaft 16 is journaled in 70 the bearings 17, 18 in the rear portions of the side frames 9, 10 and has fixed to one end, beyond the side frame 10, a belt wheel 19 which is driven by a motor 20 through a belt 21. A belt tightening device such as 75 is indicated at 22 may be employed if desired. A crank shaft 23 is journaled in bearings 24, 25 in the forward portions of the side frame 9, 10 and has fixed to one end, beyond the side frame 9, a gear wheel 80 26 which meshes with a gear pinion 27 fixed to the main shaft 16. (See Fig. 2.) The crank shaft is formed with crank arms 28, 29 adjacent each side frame and connected by crank pins 30, 31 respectively, to crank 85 disks 32, 33, the disks also being connected by a central crank pin 34. (See Fig. 6.) The crank disks rest upon relatively alined rollers 35, 36 which are carried by a shaft 37. Said shaft is journaled in bearing 90 blocks 38—38 carried by the side frames. This structure provides a support at the medial portion of the crank shaft to relieve the crank shaft bearings of the major portion of the load of the working strokes of 95 the pump.

Journaled in bearings 40—41 at the rear portions of the side frames is a beam shaft 42 on which are journaled three walking beams 43—44—45, each having a bearing 100 seat 46 engaging the shaft and secured in position by coöperating bearing caps 47. (See Fig. 4.) As the three walking beams are of duplicate construction, a description of one of them will herein suffice. Each 105 beam comprises a skeleton frame forming parallel slide ways 50—51, in which slides a crank pin block 52, hereinafter described in detail, the slide block of each beam respectively coöperating with its companion 110

crank-pin of the crank shaft. The beam frame is also provided with an orifice 53 providing clearance for non-interference with the main drive shaft 16 which projects through said orifice and the forward end of said frame has a pivoted bearing 54 for connection with the pump. The construction of the crank pin slide block (see Fig. 4) comprises a lower half-bearing 55 engaging the lower slide way 51 of the walking beam, and having laterally extended ears 56-56. An upper half-bearing 57 is also provided with laterally extended ears 58-58, the two half-bearings being secured together on the co-operating crank pin of the crank shaft, by bolts 59-59 engaging through aligned orifices in the ears of both half bearings and themselves engaged by clamp nuts 60-60.

The vertical guide rod 75 is detachably clamped in the outer medial portion of the tie yoke 11 and is secured in any desired manner at its lower end, for instance, by being screw-threaded into the flange 76 of the well-head, as shown in Figs. 1-3. The flange 76 is angularly disposed relative to the rod 75 and is secured to the well-head 77 by bolts 78, the well casing and tube being attached to said head in any suitable manner with the tube communicating with the discharge pipe 79. This construction of well-head provides a discharge having a gradual bend free from sharp turns as would retard the flow.

Links 80-81 are pivotally connected at 54 to the center walking beam 44 and to a guide head 82 secured to the upper end of an inner pump rod 83 which extends downwardly in telescopic engagement within an outer tubular pump rod 84. The guide head 82 has a split bearing 85 slidably engaging the guide rod 75, and by which the pump rod 83 is guided in its reciprocating movements.

The two outer walking beams 43-45 are respectively connected by links 86-87 to opposite sides of a cross-head 88 which is secured to the top of the tubular pump rod 84 (see Fig. 1) a suitable packing being provided between the cross-head and inner pump rod 83, as indicated at 89.

In operation, the drive shaft 16 being driven at a uniform rate of speed rotates the crank shaft 23 through the medium of the gear pinion 27 and gear wheel 26, the crank pins of the crank shaft being journaled in the slide blocks and the slide blocks slidable in their respective walking beam slide ways. As the two outside crank pins 30-31 are coincidentally aligned, the outside walking beams 43-45 will operate in unison to reciprocate the outer tubular pump rod, and as the center crank pin 34 is positioned diametrically opposite to the pins 30-31, the walking beam will reciprocate the inner pump rod in opposite directions. The ends 65 of the strokes to which the oppositely posi-

tioned crank pins raise or lower their respective walking beams are indicated by dotted lines *a-b* on Fig. 3 and as these positions are relatively angularly disposed, it follows that, when one pump rod reaches the end of a stroke the other pump rod has already started some distance on the next stroke, thereby producing a stroke lap in the operation of the pump rods, which insures a continuous pumping operation.

The invention herein described provides a pump head mechanism which as a unit may be readily moved from its normal position over the well pit to a position which will afford free access to said pit, also by positioning the entire operating mechanism between the two side frames the width of the pump connections extending into the pit is reduced to a minimum so that the supporting beams may be closely positioned together to afford a sturdy compact structure especially adaptable for use in wells in which it is undesirable or impossible to provide well pits of large dimensions. The provision of the supporting rollers for carrying the weight of the crank shaft insures long life to the crank shaft bearings and guards against any distortion of the shaft. The independent lubricating devices combine effectively with the oil distributing slide box plates to a perfect lubrication of the slide ways of each walking beam.

I claim:

1. In a pump-head, parallel walking beams, a crank shaft having opposed crank arms, intermediate crank disks and crank pins connecting the adjacent arms and disks, and slide blocks engaging the crank pins and walking beams.

2. In a pump-head, parallel walking beams having longitudinal slideways, a crank shaft having opposite crank arms, intermediate crank disks and crank pins connecting the adjacent arms and disks, and slide blocks journaled on the crank pins and slidable in the slideways.

3. In a pump-head, opposed side frames, pivoted parallel walking beams positioned between said frames, a crank shaft having crank arms adjacent each side frame, crank disks between the crank arms and crank pins connecting the adjacent arms and disks, and means operatively connecting the crank pins with the walking beams.

4. In a pump-head, opposed side frames, pivoted parallel walking beams positioned between said frames and having longitudinal slideways, a crank shaft having crank arms adjacent each side frame, crank disks between the crank arms and crank pins connecting the arms and disks, and slide blocks journaled on the crank pins and slidable in the slideways.

5. In a pump-head, a single crank shaft having opposed crank arms, intermediate
